(57) **CLAIM**

The ornamental design for a soft cassette as shown and described.

DESCRIPTION

FIG. 1 is a top perspective view of a soft cassette;

FIG. 2 is a rear perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof; and,

FIG. 8 is a bottom plan view thereof.

The broken lines in the drawings illustrate portions of the soft cassette, which form no part of the claimed design.
